COMBINATION DETERGENT DISPENSER AND CLEANING BRUSH

Walter O. Williams, 15740 Ashton Road, Detroit, Mich.

Filed Oct. 11, 1962, Ser. No. 72,070

Term of patent 14 years

(Cl. D9—2)

FIG. 1 is a top plan view of a combination detergent dispenser and cleaning brush showing my new design;

FIG. 2 is a side elevational view; and

FIG. 3 is a fragmentary front elevational view.

The side not shown is substantially the same as the side shown.

I claim:

The ornamental design for a combination detergent dispenser and cleaning brush, substantially as shown and described.
